UNITED STATES PATENT OFFICE

IRA B. FUNK, OF ALHAMBRA, CALIFORNIA

OIL-REFINING PROCESS AND APPARATUS

Application filed October 2, 1926. Serial No. 139,111.

My invention relates to improvements in the art of abstracting desired liquid hydrocarbons from vaporous hydrocarbons.

The principal object of my invention is to provide a process and apparatus for fractionating and condensing desired hydrocarbons from a mixture of vaporous hydrocarbons.

Another object is to obtain a desired fraction, or cut, having a defined end boiling point from a mixture of light and heavy hydrocarbons.

Another object is to produce a gasoline from fat absorption oil.

Another object is to produce a close cut fraction from a mixture of hydrocarbons.

Another object is to provide a cheap and efficient apparatus as a unitary structure for fractionating and condensing.

Another object is to provide a continuous process especially adapted to the production of desired hydrocarbons not heavier than commercial gasolines having an end boiling point of about 440° F.

Another object is to effect great economy in the use of steam for distillation purposes.

A further object of my invention is to provide a fractionating and condensing apparatus wherein the temperature controls will be such that scale is prevented from forming on the condenser tubes.

In the drawing, Fig. 1 is a diagrammatic view of an apparatus suitable for the process. Fig. 2 is a diagrammatic view of part of Fig. 1.

In the distillation, and/or rectification, of light products obtained from crude oil, etc., and more particularly in the distillation, and/or rectification, of re-run products especially in the distillation of natural gas gasoline from absorption oil containing the same, it is customary to provide a still 1 to which is fed through a line 2 a mixture containing desired light hydrocarbons and heavier undesired hydrocarbons. This mixture may be heated and distilled in still 1 by means of heat from a burner 3 and the use of live steam passed therein through a pipe 3a causes the lighter desired products to pass

through a line 4 to the interior of a fractionating and condensing column 5.

Part of the heavy undesired hydrocarbons is withdrawn from still 1 through a line 6, and a line 7 is provided to return heavy undesired hydrocarbons from the base of column 5 to still 1 for retreatment, or re-distillation.

Column 5 is composed substantially of two sections, the lower section A comprising a fractionating section having perforated plates or screens 8, and reflux funnels 9, all of which are constructed in a well known manner and of any desired number. Any other well known form of contact apparatus for washing vapors may be used. The second and upper section B comprises a condensing section having a plurality of perforated plates 10, reflux funnels 11, and a solid separating plate 12 having bubble caps 13 therein which separates section A from section B. Plate 12 may also be termed a water plate, but in this sense it is only used for abstracting water from condensing section B. A vapor line 14 serves to take vapors from section B to condenser 15 wherein certain fractions are condensed and passed through a line 16 to a receiver 17. The desired liquid hydrocarbons may be drawn off through a line 18, water drawn off through a line 19, while a pump 20 serves to withdraw a portion of the cold condensed desired hydrocarbons from receiver 17 and force the same back through a line 21 into the upper part of condensing section B.

A water trap 22 is provided to receive water, hydrocarbon condensate and reflux from plate 12 which passes therein through a line 23. The water is separated out and withdrawn through a line 24, part of the condensate is returned for fractionating purposes through a line 25 to section A and part of the condensate may be passed through a line 26 to mingle with the vapors passing through line 14 and condenser 15.

Condenser 15 may be constructed of a well known type, vapors passing into a head chamber 27 whence they are distributed through a plurality of tubes 28 and collect in a second head chamber 29 whence they

are withdrawn through pipe 16 to receiver 17. The condenser tubes 28 are cooled by the flow of water, or other cooling medium, passing in through a line 30 and passing out through a line 31, or vice versa. A thermometer 32 is inserted in the upper vapor space of section A and a thermometer 33 is inserted in line 14 at its outlet from section B, and suitable valves are provided in the various lines.

Inasmuch as the process may be operated under superatmospheric pressure, up to 500# pressure, a pressure regulating valve 34 is inserted in line 35 for controlling the discharge of incondensable gases from receiver 17.

In the operation of the process, as an illustration, fat absorption oil containing natural gas gasoline is supplied through line 2 to the still 1 wherein it is heated by burner 3 and distilled with live steam supplied through line 3a, the distilled vapors and intermingled steam passing through line 4 to the column 5. The pump 20 is then started for supplying cooled condensate from receiver 17 to the upper plate of condensing section B where the same percolates downwardly and a portion passes through line 23 to the water separator 22. The ascending vapors from line 4 are partially condensed and fractionated in section A and desired uncondensed portions pass through the bubble caps 13 to be condensed in section B. The temperature of the vapors in the upper portion of section A, just below plate 12, as indicated by thermometer 32, normally controls the quality of the product obtained in receiver 17, and depends on the quantity of condensate pumped into section B, passing through separator 22 and line 25 into section A. The quantity of condensate thus passed through section B may be controlled by the quantity by-passed through line 26.

The passage of vapors and steam through bubble caps 13 to be acted on in the condensing section B causes condensed water, as well as hydrocarbon condensate, to be abstracted through pipe 23 thereby eliminating the condensing and re-boiling effect of water in section B and thus obtaining a more closely cut product.

The action of the reflux passing through line 26 on the vapors passing through line 14 is to reduce their temperature to a point where the temperature differences on the inside and outside of tubes 28 prohibits the formation of any substantial amount of scale on the outside thereof and at the same time it aids in the obtaining of the desired product in receiver 17. This action is an aid to the final condensation in condenser 15 because an increased proportion of heavier materials is introduced into line 14 thus lowering the vapor pressure. Also the condensate cycled through line 21 to con-

densing section B aids, by direct contact, in lowering the temperature therein.

In this manner, the capacity of condenser 15 may be a minimum, thus offering a very cheap construction.

By making fractionating section A and condensing section B a unitary structure, an outside primary condenser is eliminated. Also still 1 may be placed in the lower part of column 5 in a well known manner and the distillation, fractionation and condensation may all take place in the column 5.

In the above process, it will be seen that condensation of desired light hydrocarbons takes place in two stages with continuous cycling of part of the condensate through the condensing section B.

Inasmuch as the scaling of condenser tubes takes place at temperatures at, or above, the boiling point of water at whatever pressure the process is operated, it is therefore highly desirable that the temperature of vapors entering condenser 15 should be below said boiling point in order that condenser 15 shall have the greatest efficiency per unit of size. This is accomplished by passing condensate through line 26 to mingle with the vapors in line 14 wherein the vapor pressure is thus lowered due to the volume of condensate containing heavier fractions supplied thereto.

By thus controlling the quantity of condensate cycled, the desired hydrocarbons may be recovered in receiver 17 and will have a definite end boiling point.

I claim:

1. The process of recovering desired liquid hydrocarbons from a mixture of vaporous hydrocarbons which comprises vaporizing a mixture of light and heavy liquid hydrocarbons and mixing steam therewith, fractionating the mixture to eliminate undesired heavy hydrocarbons, condensing the light desired hydrocarbons in two stages, continuously cycling a portion of the condensed light desired hydrocarbons through the vaporous light desired hydrocarbons in the first condensing stage and separating and withdrawing condensed steam from the reflux liquid in the first condensing stage.

2. The process of recovering desired liquid hydrocarbons from a mixture of vaporous hydrocarbons which comprises vaporizing a mixture of light and heavy liquid hydrocarbons and mixing steam therewith, fractionating the mixture to eliminate undesired heavy hydrocarbons, condensing the light desired hydrocarbons in two stages, continuously cycling a portion of the condensed light desired hydrocarbons through the vaporous light desired hydrocarbons in the first condensing stage and separating and withdrawing condensed steam from the reflux liquid in the first condensing stage; the final condensation taking place at a tem-

perature below the boiling point of water.

3. The process of recovering desired liquid hydrocarbons from a mixture of vaporous hydrocarbons which comprises vaporizing a mixture of light and heavy liquid hydrocarbons and mixing steam therewith, fractionating the mixture to eliminate undesired heavy hydrocarbons, condensing the light desired hydrocarbons in two stages, 5 continuously cycling a portion of the condensed light desired hydrocarbons in direct contact with the vaporous light desired hydrocarbons in the first condensing stage and separating and withdrawing condensed 10 steam from the reflux liquid in the first condensing stage.

4. The process of recovering desired liquid hydrocarbons from a mixture of vaporous hydrocarbons which comprises vaporizing a mixture of light and heavy liquid hydrocarbons and mixing steam therewith, 20 fractionating the mixture to eliminate undesired heavy hydrocarbons, condensing the light desired hydrocarbons and steam in two stages, continuously cycling a portion of the 25 condensed light desired hydrocarbons through the vaporous light desired hydrocarbons in the first condensing stage and removing water from the mixture in the 30 first condensing stage.

5. Apparatus for refining oil comprising a still, a fractionator, a primary condenser, a final condenser, a vapor line forming a connection between the condensers, means to 35 pass oil vapors from the still through the fractionator and primary condenser, means to pass condensate from the primary condenser into the fractionator and vapor line, and means to pass condensate from the final 40 condenser into the primary condenser.

Signed at Los Angeles, in the county of Los Angeles and State of California, this 27th day of September, A. D. 1926.
